UNITED STATES PATENT OFFICE.

EMIL TIETZE AND GOTTLIEB SCHULER, OF NEW YORK, N. Y.

VENTILATOR.

Application filed February 17, 1925. Serial No. 9,790.

To all whom it may concern:

Be it known that we, EMIL TIETZE and GOTTLIEB SCHULER, citizens of the United States, and residents of the city of New York, borough of the Bronx, in the county of Bronx and State of New York, have invented a new and Improved Ventilator, of which the following is a full, clear, and exact description.

10 This invention relates to ventilators and more particularly to a window or sash ventilator, an object of the invention being to provide a ventilator of this character which will constitute a portion of the window or 15 sash, which will be air and water-tight when closed, which can be opened to any desired degree, and which will shed rain and snow when open.

15 A further object is to provide a ventilator 20 which constitutes a portion of a window or sash, the several movable slats thereof being of glass mounted in suitable supporting members and having improved operating means which enable the slats to be opened 25 to any desired angle, and which when closed securely lock the slats in closed position so as to prevent unauthorized movement of any or all of the slats by some one outside of the window.

30 With these and other objects in view, the invention consists in certain novel features of construction and combinations and arrangements of parts which will be more fully hereinafter described and pointed out 35 in the claims.

In the accompanying drawings—

Figure 1 is a view in elevation of a window or sash equipped with my improved ventilator;

40 Figure 2 is a view in longitudinal section on the line 2—2 of Figure 1, showing in dot and dash lines an open position of the ventilator;

Figure 3 is a fragmentary view in section 45 on the line 3—3 of Figure 1;

Figure 4 is a perspective view of a slat holder.

1 represents a window or sash or any frame which may support at its end portions glass panes or lights 2 and 3, respectively, the intermediate portion between the panes 2 and 3 providing an opening for the accommodation of our improved ventilator, which will be hereinafter described.

It is of course to be understood that we 55 do not limit ourselves to the position of the ventilator relative to the sash as it may be at any desired point of the sash.

In the sides of the frame 1 metal plates 4 and 5, respectively, are secured and countersunk. To these plates 4 and 5 slat holders 6 are pivotally connected. These slat holders 6 have longitudinal grooves 7 therein receiving the slats 8 which are suitably packed as shown at 9 to make them air tight 60 and prevent rattling or possibility of breakage.

The slat holders 6 at one side of the frame 1 are provided with perforated lugs 10 which receive screws 11 secured in the 70 plate 5 and provide pivotal mounting for said holders. The holders 6 at the other ends of the slats 8 are made with rearwardly projecting arms 12 which are pivotally supported between the ends on screws 13 75 secured in the plate 4. The free ends of these arms 12 are pivotally connected to a link 14, and, as the pivotal means, I have shown screws 15 which are projected 80 through the arms and screwed into the link 14. This link 14 compels all of the arms to move together and hence compels all of the slats to move together.

A locking lever 16 is pivotally connected 85 between its ends to the link 14, as shown at 17, and has a laterally offset shoulder 18 adjacent its inner end which is adapted to engage the inner edge of the link 14 and limit the pivotal movement of the lever 16 90 in one direction.

A coil spring 19 connects the outer end of this lever 16 with a fixed arm 20 on plate 4 so as to hold the lever in normal position and exert a pressure on the lever and the link 14 to hold the slats in closed position 95 or return them to such position.

The inner end of this lever 16, when the slats are in closed position, lies against the upper portion of one of the slat holders 6 so as to prevent any possibility of some one outside of the ventilator manually moving or pivoting the slats. This lever therefore constitutes an automatic lock as well as a means for opening the ventilator slats.

A chain 21 is secured to the free end of lever 16 and has, preferably, a ring 22 at its lower end for the reception of a finger to exert a pull on the chain to open the venti-

lator, and when the ventilator is opened to the desired degree any link of the chain 21 is caught over a fixed pin or hook 23 on the frame 1 to hold the ventilator in this position.

We would call particular attention to the shape and construction of the slat holders 6, one of which is shown in perspective in Figure 4.

10 The outer members of the grooved slat holders extend below the inner members thereof and have webs 24 thereon against which the edges of the slats are seated. The inner member of each slat holder has an 15 enlargement 25 thereon which when the ventilators are closed lies in a plane above the upper edge of the slat below so that any attempt to move a slat upwardly will only cause the same to engage the enlargement 20 25 of the slat holder above and prevent such movement. The uppermost slat may be confined in any approved manner but we have shown as a simple means small angle brackets 26 secured to the uppermost slat 25 holders and projecting over the edge of the uppermost slat.

Figures 1 and 2 illustrate clearly the position of the slats when closed, showing that the several slats and their holders are so shaped that they provide a tight closure which is securely locked by the lever 16. Furthermore, as above explained, the slats are securely locked and held in place against either pivotal or other movement by an 30 35 unauthorized person outside of the window.

When it is desired to open the ventilator it is simply necessary to exert a pull on the chain 21, this pull first moving the locking lever 16 out of locked position and then a 40 continued pull on the chain will draw the link 14 downwardly and cause all of the slats to pivot and move to the desired angular position and held in such position, when one of the links of the chain 21 is caught 45 over the pin or hook 23. When the chain is released the spring 19 will return the parts to closed and locked position.

Various slight changes and alterations 50 might be made in the general form of the parts described without departing from our invention, and hence we do not limit ourselves to the precise details set forth but consider ourselves at liberty to make such slight

changes and alterations as fairly fall within the spirit and scope of the appended claims. 55

We claim:

1. The combination with a window frame having transparent panes and an opening therein, a plurality of overlapping transparent slats adapted to close the opening, 60 holders at the ends of the slats pivotally connected to the frame, a link connecting the holders at one side of the frame and compelling them to move together, and a pivoted lever on the link engaging one of the slat 65 holders and functioning to lock the slats in closed position.

2. The combination with a window frame having transparent panes and an opening 70 therein, a plurality of overlapping transparent slats adapted to close the opening, 75 holders at the ends of the slats pivotally connected to the frame, a link connecting the holders at one side of the frame and compelling them to move together, a pivoted lever on the link engaging one of the slat 75 holders and functioning to lock the slats in closed position, said lever having a shoulder thereon adapted to engage the link when moved to unlocking position, a spring holding the lever normally in locking position, a chain engaging the lever and adapted to be manually operated to release the lever from locking position and move the slats to open position, and a fixed device adapted to receive a link of the chain and hold the slats in open position.

3. The combination with a frame having an opening therein, plates fixed to the sides of the frame, slat holders pivotally connected to the plates, glass slats in said holders of a width to overlap each other and form a tight closure when in one extreme position, arms on the slat holders at one side of the frame, a link connecting said arms, a lever pivotally connected between its ends to the link and having a shoulder thereon engaging the link when moved to unlocking position, a spring connecting the lever with one of said plates and exerting a pull thereon to hold the lever in position back of one of the slat holders and also to hold the slats in closed position, and means for moving the lever to operate the slats.

EMIL TIETZE.
GOTTLIEB SCHULER.
